MILK CARTONS, ETC.

John C. Mercer, Pittsburgh, Pa., assignor of ten percent to Archworth Martin, Pittsburgh, Pa.

Application July 29, 1957, Serial No. 674,782

3 Claims. (Cl. 229—17)

My invention relates to containers for liquid such as milk, orange juice, etc., that is particularly put up for domestic consumption.

One object of my invention is to provide a one-piece structure that can be made from a one-piece cardboard blank or the like and which can nevertheless be more effectively opened and closed for repeated pourings therefrom than various types of containers heretofore employed.

Another object of my invention is to provide a container of the character referred to which when after it is opened will be more sanitary than various types heretofore employed, by reason of the improved cover which I employ.

Another object of my invention is to provide a one-piece blank for forming a complete container, that can be shipped in the flat condition and readily opened up at the dairy for the reception of a liquid and which can be thereafter sealed in an improved manner.

Figure 1 is a view of the blank from which the container is formed.

Fig. 2 shows the blank folded to form a container, but with the top flaps open.

Fig. 3 is a perspective view on an enlarged scale showing the upper portion of the completed carton after it has been opened for the pouring of liquid therefrom.

Fig. 4 shows the structure of Fig. 3 closed.

Fig. 5 is a view taken on the line 5—5 of Fig. 4.

Fig. 6 is a view taken on the line of 6—6 of Fig. 4.

The blank comprises panel portions 2, 3, 4 and 5, the panel 5 having a wing or lip 6 that is glued to the inner surface of the panel 2, as shown in Fig. 2.

The bottom flaps 7, 8, 9 and 10 on the lower ends of the panels are folded inwardly and glued together to provide the closed bottom for the container.

The panel 3 has a top flap 21 that is secured in closed position by lips 18, 22 and 28 which are glued to the panels 4, 2 and 5, respectively, when closing the container. The milk or other fluid can be filled into the container before closing this top flap 21, or can be filled through the pouring opening 20 after the flap is secured in place. The lip 28 on the cover member 21 is upturned at its rear edge and sealed to the panel 5 shown in Fig. 5. This not only reduces danger of leakage but gives stiffness to the structure.

The topmost cover member 11 has areas 12 and 17 divided by a score line to permit of flexing movement of the portion 17 when opening and closing the container. The part 12 of this cover member has a lip 13 that is bent over a folded edge 19, that is creased along the line at 23. This not only provides a good seal at that

2

corner of the container, but gives a stiffening whereby a sealing roller that moves along the groove 25 is enabled to make a good seal at 19. The depression 24 in the side wall 5, as shown in Fig. 5 serves to support the inner cover member 21 from dropping.

5 The top cover member 11 has wing 14 that is glued to the side wall 4. A perforated line 15 is provided where the member 17 and the member 14 meet so that the outer corner of the member 17 can be lifted from the position shown in Fig. 4 to that shown in Fig. 3 and pouring effected through the opening 20. The cover member 17 has a depression 16 that serves as a cork or stopper for the opening 20 through the inner cover member 21. This opening could, of course, be circular. 10 After a container has been opened, the cover member 17, when closed, will be lightly held against flapping upwardly by some snap action at 23—29, (Fig. 5).

Initially, there need not be an actual opening at 20 but there can be a disc-like area supported thereat by 15 weakened lines, until the customer raises the upper lid. There is, thus no danger of leakage since the inner cover is connected at all four edges to the vertical walls of the container.

20 After the container has been opened through the lifting of the upper cover portion 17, the disc member at 25 20 will be torn out to form the pouring opening. Even after the container has been partially emptied, danger 25 of leakage is minimized because of the plug-like member 16 that is pushed into the opening 20.

30 I claim as my invention:

1. A container of cardboard or the like for liquids, that comprises a body portion having four vertical panels and closed at its lower end, two superposed cover flaps secured to the upper edges of the panels, the lower 35 flap having a pouring opening therethrough adjacent to an upper corner of the container and the upper flap serving as a closure for the opening, a downturned lip on the upper flap and secured to one of the vertical walls adjacent to the said opening, the lip being connected 40 to its flap by a weakened tear line, and a second downturned lip carried by the upper flap in position to engage against the other vertical wall at said corner and having a horizontal yieldable rib on its inner face, the last-named vertical wall having a horizontal depression 45 into which said rib will enter with a snap action upon closing movement of the upper flap, the last-named flap being bendable upwardly at said corner, along a diagonal line that extends from one lip to the other adjacent to the mid zone of the flap, in order to expose 50 the pouring opening when the tear line is ruptured and the said rib raised from said depression.

2. A container as recited in claim 1, wherein the bendable portion of the flap has a plug-like closure element at its underside in position to enter the said pouring 55 opening.

3. A container as recited in claim 2, wherein the closure element and the wall of the pouring opening have tapered fit with one another.
